UNITED STATES PATENT OFFICE.

WISTER C. WILLIAMS, OF DECATUR, ILLINOIS, ASSIGNOR TO McLAUGHLIN COAL REDUCTION COMPANY, OF DECATUR, ILLINOIS, A CORPORATION OF SOUTH DAKOTA.

PULVERIZING APPARATUS.

Application filed April 10, 1922. Serial No. 551,012.

This invention relates to improvements in pulverizing apparatus and more particularly to the removal of the pulverized material from the pulverizing machine after it has reached a predetermined degree of fineness.

In certain types of pulverizing machines the pulverized material is removed continuously during the operation of the apparatus by withdrawing the same in suspension in an air current, the theory being that only those particles which are sufficiently fine will be carried off in a current of air having a certain velocity. It has been found, however, that in order to prevent the withdrawal of particles which are not sufficiently fine, the movement of material or the velocity of the current of air carrying the particles in suspension must be so slow that much of the material possessing a sufficient degree of fineness is left behind. This results in a reduction of the capacity and efficiency of such machines and apparatus.

The primary object of this invention is to provide a method of and apparatus for increasing the capacity and efficiency of a pulverizing machine of this type.

The invention consists in the novel combinations, constructions and arrangements for carrying out the above stated objects and such other objects as may appear from the following specification and claims.

The invention is illustrated in a preferred embodiment in the accompanying drawings wherein:

Fig. 1 is a view somewhat diagrammatic in form of the apparatus showing in elevation a form of pulverizing machine.

Fig. 2 is a longitudinal vertical section of a type of pulverizing machine shown in Fig. 1.

Fig. 3 is a transverse section taken along the line 3—3 of Fig. 2, and

Fig. 4 is a fragmentary detailed view of the air blast nozzles.

Like characters of reference indicate like parts in the several figures of the drawings.

The construction herein shown, while particularly adapted for use in pulverizing fuel, may be employed for pulverizing other material susceptible of pulverization in this type of apparatus.

For the purposes of illustration I have shown a pulverizing machine designated generally as 10 and which will be described

more in detail hereinafter. Referring particularly to Fig. 1, the material to be pulverized is fed from the chute or other conveying means 11 into the receiving hopper 12 from which it is carried into the interior 60 of the pulverizer. Within the pulverizer are means for suspending in the air therein the finest particles of material without materially disturbing the material which is undergoing the process of pulverization. 65 These fine particles together with such other coarser particles as may be suspended in the air are withdrawn from the interior of the pulverizer through a pipe 13 connected to the intake side of a blower or fan 14 which 70 creates sufficient suction in the interior of the pulverizer to withdraw the suspended particles.

The suspended particles are passed through the blower and into a cyclone separator 15 75 through the pipe 16. The cyclone separator is of any well known type and is adapted by reason of the centrifugal force of the whirling air and particles to separate the coarser particles from the finer particles. 80 The velocity of the current carrying suspended particles into the cyclone separator 15 is adjusted so that all the particles which have not been pulverized to a sufficient degree of fineness are thrown out and fall into 85 the hopper 17 at the base of the separator. Such coarser particles preferably pass directly through the spout 18 and into the receiving hopper 12 and from thence enter the pulverizer to be subjected to further pul- 90 verization.

The particles of pulverized material of the required degree of fineness remain suspended in the air and are withdrawn from the cyclone separator through the pipe 19 95 by means of the blower or fan 20. By means of the control of the suction exerted by the blower 20, an additional control is had of the separation of the fine from the coarser particles within the separator 15. The current of air carrying the fine particles is passed through the pipe 21 into any suitable form of separator 22 adapted to remove the fine particles from the air. For the purpose of illustration I have shown a separator 100 having the sides thereof formed of fabric 23 whose mesh is sufficiently fine to prevent the escape of the fine pulverized material while permitting the escape of the air. The pulverized material then falls into the storage 105 110

hopper 24 from which it may be withdrawn through the spout 25.

The particular form of collector 22 forms no part of my invention and may be of any 5 suitable type capable of depositing the pulverized material so that it may be collected.

The particular details of the pulverizer form no part of my invention. Any suitable 10 type of pulverizer may be used in which the removal of the pulverized material is affected by means of suspension of the fine 15 particles in a current of air. The particular type of pulverizer illustrated comprises a rotary drum 26 having within the interior 20 thereof a plurality of free rolling crushing elements consisting of cylindrical rollers, 27 which extend the length of the drum and are preferably of a multiplicity of different 25 diameters. Pulverization is effected by the abrasive action of the rollers on one another 30 which action is increased by the employment of rollers of different diameters. In order to insure relative movement of the rollers during the rotation of the drum 35 small cleats 28 are secured to the interior of the drum in order to cause displacement of the rollers during rotation of the drum.

The drum is centered on supports 29 and 30 provided with bearing rings 30 by means of which the drum is revolutely supported upon the rollers 31 which are grooved to correspond with the rings 30. The rollers are rotated by the worm and gear 32 and 33 through the shaft 34, the rotation of which 35 causes the rotation of the drum.

The material to be treated is supplied to the hopper 12 from which it passes through the conduit 35 to the cylindrical casing 36, supported at opposite ends upon the supports 29. The supports 29 are provided with rings 37 and set screws 38 for holding the casing 36 centrally relative to the pulverizing drum.

Arranged within the casing 36 is a screw 45 conveyor 39 the shaft 40 of which extends through the caps 41 which close the opposite ends of the casing 36, the shaft being provided at one end with a driving pulley 42. In order to distribute the material evenly 50 lengthwise of the drum, the casing 36 is formed with a helical delivery edge or slot 43, the high point of which is at the end of the casing into which the material is delivered and the low point near the other end 55 of the casing. At the discharge end of the drum is arranged a housing 44 from which leads the pipe 13 running to the suction fan 14.

For the purpose of initially suspending 60 the fine material so that the same may be drawn by suction by the fan 14, compressed air is supplied to the pipe 45 leading into the housing 44 and connected with the horizontal pipe 46 having inclined air nozzles 65 47. The jets of air escaping through the

nozzles 47 are directed obliquely to the body of material within the drum as shown in Figs. 3 and 4 and are regulated to be of sufficient strength to suspend substantially all of that portion of the available material 70 which possesses the required degree of fineness. The available material is that material exposed to the action of the jet. It is not contemplated to agitate the material in the drum sufficiently to interfere materially 75 with the process of pulverization. In suspending all such fine material it is inevitable that certain particles of material not sufficiently fine are also suspended in the air in the drum. Such suspended particles are 80 withdrawn in the manner stated above by a suction of air sufficient only to withdraw the suspended particles and not strong enough to interfere with the bulk of material in the drum which is not pulverized 85 sufficiently fine. But in order to accomplish efficient operation and to increase the capacity of the pulverizer it is inevitable that a certain percentage of the suspended particles withdrawn have not yet been pulverized 90 to the required degree of fineness. Such particles are returned for further pulverization in the manner before described.

By regulating the velocity of the air jets 95 through the nozzles 47 and the suction produced by the fans 14 and 20 it is possible to not only vary the degree of fineness of the finished product but to regulate the operation of the apparatus so that the process of withdrawing the fine material removes 100 as small a percentage as possible of the coarser particles which are to be returned for further pulverization consistent with efficient operation.

Instead of returning the coarser particles 105 to the pulverizer for further treatment this material may be withdrawn from the apparatus and marketed as "sea coal" for use in foundries. The product is of very considerable value in this connection on account 110 of the uniformity in size of the particles. It is free from extremely fine powder present in most sea coals and which is detrimental to the product when used in molding.

115 I claim:

1. A pulverizing and sizing system including feed mechanism, pulverizing mechanism, means for creating suction through said pulverizing mechanism, a separator into which said suction means delivers its air current, a second suction means beyond said separator in the direction of air travel, a second separator into which said second suction means delivers its air current, and means 120 for returning material from said first separator to said pulverizing mechanism.

2. In an apparatus of the class described, in combination, a pulverizer, feeding means therefor, a closed air conduit leading from 125

said pulverizer, means for agitating the material by an air blast, means independent of said agitating means for creating air current in said conduit for withdrawing particles of material from said pulverizer, a separator into which said air currents are directed, a second suction means in said circuit beyond said separator, and a screening

device into which said second means delivers said air current wherein the particles of matter may be removed from said current and collected and means for delivering the material from said first separator to said pulverizer for further treatment. 10

WISTER C. WILLIAMS.
